MECHANISM FOR CONVERTING A RIFLE FROM
SEMI-AUTOMATIC TO AUTOMATIC FIRINGPier Carlo Beretta, Via Siepi 6, Gardone
Valtrompia, ItalyFiled Apr. 6, 1960, Ser. No. 20,394
Claims priority, application Italy May 23, 1959
2 Claims. (Cl. 89—140)

The regular Italian rifle of the Garand 30 M1 type is a semi-automatic rifle and it fires in succession shots corresponding to single operations of the trigger by the marksman.

The present invention has for its object an arrangement for obtaining selectively with the same rifle, such as said Garand rifle, a semi-automatic operation shot by shot, or else, an automatic operation. Obviously, it is possible to obtain, through an automatic operation of the rifle, a larger volume of fire and, thereby, a much higher efficiency than that provided with semi-automatic operation. On the other hand, it is also desirable to retain on a rifle the characteristics of semi-automatic operation which may be undoubtedly useful in the case of an accurate and precise firing. In order to ensure a number of shots corresponding to the requirements of automatic operation, the arrangement considered has been provided for its application to a Garand rifle with a box-shaped magazine in place of the original clip charger.

According to the invention, there is incorporated with the components of the semi-automatic rifle and with the box-shaped magazine a member adapted for a preliminary stage of automatic operation to disconnect the sear or detent with reference to the trigger when the bolt and the operating rod have reached the position corresponding to the end of the introduction of a cartridge into the barrel. The disconnection of the hammer and, consequently, the firing of the cartridge are performed automatically and are repeated in succession until the magazine is exhausted or else until the marksman has released the pressure exerted by him on the trigger.

The accompanying drawings illustrate a preferred embodiment of the invention, to wit:

FIG. 1 is an elevational view of one side of a gun with part thereof shown in section, and with the bolt in its closed position;

FIG. 2 is a similar side view of the rifle as seen from the opposite side together with a cross-section through the pivot of the selector lever;

FIG. 2a is a partial sectional view taken along the line 2a—2a of FIG. 2 and looking in the direction of the arrows;

FIGS. 3, 4 and 5 illustrate the successive stages of the automatic operation of the rifle;

FIG. 6 illustrates a type of control lever employed in this gun;

FIG. 7 illustrates a selector lever of the type employed in this gun;

FIG. 7a is a view looking at the left side of the lever in FIG. 7;

FIG. 8 is a view of the device which interconnects the selector lever and the automatic control lever;

FIG. 8a is a view looking at the left side of the device shown in FIG. 8;

FIG. 9 illustrates in contradistinction the semi-automatic operation of the rifle shot by shot.

In the accompanying drawing, the reference letters designate the original parts of regular Garand rifles and the arrows indicate the direction in which parts move (unless otherwise indicated), while the reference numbers designate the different components of the novel arrangement incorporated with the rifle, according to the in-

2

vention. It should be understood furthermore that the operations ensuring the successive hammer setting and releasing steps, the introduction of the cartridges and the extraction of the cartridge case after firing, etc. are executed in conformity with the original design of the regular rifle with a reciprocation of the bolt and of the operating rod simultaneously with the action exerted by the marksman on the trigger. In particular, the following reference letters designate the following parts:

- 10 a designates the bolt progressing and receding alternately under the action of the recovering springs acting against the thrust exerted by the shot.
- 15 b designates the receiver extending above the trigger casing.
- c designates the hammer.
- d designates a plunger on the spring acting on the hammer and enclosing said spring.
- e designates the trigger with the projection e' (primary sear) there for engagement with the hammer.
- 20 f designates the secondary sear provided with a projection f', the sear being pivotally secured to the body of the trigger.
- g designates the operating rod on which the recovering spring acts.

As already mentioned, FIG. 1 is a side view of the rifle as seen from the right hand side, the bolt being in its closed or forward position.

Turning now to the reference numerals relating to the novel incorporated parts, 1 designates the automatic control lever pivotally secured to the side of receiver b at point 3, the front end of said lever forming a shaped projection 2. The lever is urged by a spring 4 (mounted in a recess 4' in lever 1 and guided by a pin 4" on receiver b to bear against the latter) so as to constrain the projection 2 to engage the lower side of the operating rod g which is subjected to the action of the conventional recovering spring which is not illustrated for sake of clarity.

It should be remarked that the lever 1 pivoting round the point 3 may assume different angular positions in a vertical plane under the action of the spring 4 according to the position assumed by the rod g which reciprocates simultaneously with the bolt.

FIG. 2 is a view of the rifle from the left hand side and in addition to the parts illustrated in FIG. 1, it shows a selector lever 7 which is adapted to assume as required by the marksman one of two angular positions designated by Ia and IIa respectively corresponding to semi-automatic shot by shot operation and automatic operation.

The lever 7 has a slot 7' which engages with a rectangular portion 8' at one end of pivot 8 which passes through the forward end of the receiver b and carries at its opposite end a small plate or guide bracket 9 folded into channel shape at its lower end 10 for engagement by the front end of the lever 1 controlling automatic firing. The lever 7 is subjected to the action of the "over-center" type spring 7" guided in recess 7" in the lever and secured to the receiver b, the spring holding 7 in either of its positions Ia or IIa. It will be remarked that upon shifting by hand the lever 7 from the position Ia into the position IIa there is obtained a rotary movement of the pivot 8 and consequently of the small plate 9.

The different positions assumed by the latter define through its projecting end or else through its upper nose 11 different angular positions in a vertical plane for the lever 1. The front end of the lever 1 is raised in fact by the projecting end 10 or else it is urged downwardly by the upper nose or lug 11. Thus the rear end 1' of said lever 1 has a sloping cammed surface (FIG. 1) which engages or disengages the sear f with reference to the hammer, the projection or lug 10 limiting the pivotal

motion of lever 1 during automatic operation so end 1' will not become disengaged from the sear f.

FIG. 3 is a view from the right hand side of the first stage of automatic operation; the selector lever is set by the marksman in the position IIa for automatic firing. The marksman has drawn the trigger e rearwardly while the bolt a and the rod g are at the rearmost end of their receding motion after the firing of a shot. The hammer c has entered its inverted position and is not engaged by projection e'. The end of the lever controlling automatic firing is raised to the maximum of the motion allowed by the positions assumed by the lever 7 and by the rod g and by the thrust exerted by the spring 4. Consequently the rear end 1' of the lever 1 is lowered to a maximum and its cammed surface engages the sloping surface f'' formed on the secondary sear f. The rear end c' of the hammer has not yet engaged the projection f' on the sear f since the bolt engages in its rearmost position the back of said hammer and holds it completely reversed and facing downwardly.

FIG. 4 illustrates the second stage of automatic operation. The bolt a and the operating rod g move forwardly under the action of the recovering spring and are about to reach their final closing position. In such a position, the rod g and the lever 1 are in contact with each other under the action of the spring 4 along the sloping planes or cam surfaces 5 and 6 formed on said rod and on said lever, respectively. Consequently, the lever 1 has a tendency to be lowered at its front and to be raised at its rear end. As a result of the shape given to the rear end 1' of lever, the sear f pivoted on trigger e is shifted forwardly so as to engage its projection f' with the cooperating projection c' on the hammer and to set the latter in its ready-to-fire position. The engagement of said hammer with the sear has for its object to prevent said hammer from firing a further cartridge before the bolt has reached the end of its closing motion. This cuts out the possibility of premature firing or firing outside the barrel.

FIG. 5 illustrates the third and final stage of automatic operation. The bolt a and the operating rod g have reached their final closing position. As a result of the final stroke executed by the rod g, the end 2 of the lever is now in contact with the underside of the rod g so that forward end of the lever 1 has turned by a further angle downwardly while its rear end has raised and urged again rearwardly the sear f, which latter has therefore disengaged the hammer. The hammer in its turn hits the striker and produces the firing of the cartridge simultaneously with the closing of the rifle by the gas check.

The cycle of operations is then resumed starting from the position illustrated in FIG. 3.

FIG. 9 illustrates the operation of the rifle firing shot by shot in a semi-automatic manner. The marksman sets for such an operation the selector lever 7 in its position Ia. The pivot 8 turns consequently together with the small plate 9 rigid therewith and the upper nose 11 projecting with reference to said plate engages the upper side of the lever in the front section of the latter.

Thus the lever 1 sinks through its front end and is no longer subjected to the action of the operating rod g while its rear end rises and this shifting movement provides a

complete disengagement (see x) between the lever end 1' and the sear f at any moment, so that said sear is henceforward adapted to execute, without any further connections, the operations provided in accordance with the original design of the fire-arm i.e. the semi-automatic operation controlled shot by shot by the action of the marksman on the trigger.

What I claim is:

1. In a semi-automatic rifle of the Garand type or the like wherein upon the firing of said rifle a bolt and operating rod reciprocate in a receiver rearwardly to cock a hammer and then move forwardly to chamber a cartridge and lock said bolt before release of the cocked hammer, a device for rendering said rifle fully automatic comprising a trigger, a sear pivotally mounted on said trigger and movable therewith, upon movement to and retention of said trigger in its fired position, to engage and hold said hammer in its cocked position, a cam surface on said operating rod, a spring-loaded lever extending longitudinally of said rifle and pivoted intermediate its ends to the side of said receiver, said lever having a cammed surface on the rear end thereof disposed to engage said sear when said trigger is in its fired position, said lever having a projection on the forward end thereof positioned to be in the path of movement of said operating rod when said trigger is in its fired position, a manually adjustable selector bracket mounted on one side of said receiver and adjustable to render said rifle automatic or semi-automatic, said bracket having spaced upper and lower lateral lugs thereon, which, when said bracket is adjusted for automatic operation of said rifle, extend respectively over and under the forward end of said lever, whereby upon the firing of said rifle and the cocking of said hammer during automatic rifle operation, said operating rod moves forwardly so that the cam surface thereon engages said projection, thereby causing said lever to be pivoted against its spring load, the forward end thereof to be urged downwardly against said lower lug, and the cammed surface on the rear end of said lever to pivot said sear on said trigger to release said hammer from its cocked position.
2. In a semi-automatic rifle of the type defined in claim 1 wherein said bracket is fixed to one end of a shaft rotatably mounted in said receiver, said shaft having a handle fixed to the opposite end thereof, whereby upon rotation of said handle toward the rear of said rifle from its automatic to semi-automatic position, said bracket is pivoted and moves its lower lug from beneath the forward end of said lever while urging said upper lug against the upper side of said lever to thereby pivot the latter to remove its projection from the path of said operating rod and its cammed rear end from engagement with said sear and rendering the rifle semi-automatic in operation.
